UNITED STATES PATENT OFFICE.

ULYSSES GRANT CAVE, OF LOUISVILLE, KENTUCKY, ASSIGNOR TO MULTIPLEX SALES
REGISTER COMPANY, OF LOUISVILLE, KENTUCKY, A CORPORATION OF SOUTH
DAKOTA.

AUTOGRAPHIC REGISTER.

Specification of Letters Patent. Patented Jan. 25, 1916.

1,169,528.

Application filed November 7, 1914. Serial No. 870,848.

To all whom it may concern:

Be it known that I, ULYSSES GRANT CAVE, a citizen of the United States, resident of Louisville, in the county of Jefferson and State of Kentucky, have made a certain new and useful Invention in Autographic Registers; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a side view of the invention, shown as adjusted pivotally in dotted lines. Fig. 2 is a plan view of the invention. Fig. 3 is a section on the line 3—3, Fig. 1, showing the casing as turned down upon one side in dotted lines. Fig. 4 is a plan view of the invention, with parts broken away, the casing being turned down upon one side. Fig. 5 is a section on the line 5—5, Fig. 1. Fig. 6 is a section on the line 6—6, Fig. 1. Fig. 7 is a detail side view of the hand rest, and parts adjacent thereto, said rest being shown as adjusted pivotally in dotted lines.

The invention has relation to autographic registers of comparatively large size, to be placed upon a counter or other support, where it is intended to remain and be operated.

The invention consists in the novel construction and combinations of parts, as hereinafter set forth.

35 In the accompanying drawings, illustrating the invention, the numeral 1, designates a frame or casing, which, as the register is designed to provide for the entry and recording of sales of a number of different kinds or classes, has a suitable number of peripheral faces, one face for each class of sales, four faces usually, each face having preferably a platform plate 2, two rotary spindles 3 and 4, designed respectively to receive the paper supply or feed roll 5 of paper, and for winding of the paper to constitute the record roll 6, the paper passing from the supply roll longitudinally over the platform plate, the upper sheet or sheets of paper 7, 7' passing then over a guide and feed roller 8, out of the casing, all as described and shown particularly in my co-pending application for patent executed of

even date herewith, Serial No. 848,047, filed 55 June 29, 1914. Each spindle 3 carries a spool 3', upon which the supply roll 5 of paper is mounted, said spool being caused to turn with the spindle by suitable means, as a spring device 3² upon the spindle and engaging the center perforation of the spool.

Inasmuch as the register is comparatively heavy, the casing thereof is pivoted centrally, the shaft or pivot 5', having bearings 65 in sides a, a', of a base b.

To facilitate the operation of the machine, it is desirable to provide a means for operation of the record spindle, to feed the upper paper sheets and wind the lower paper sheets upon the record roll, which shall be common 70 to each of the four record spindles of the machine and which shall not move with the casing, said means of operation being usually a crank handle c, having a releasable connection with each record spindle as it comes 75 uppermost in the rotary movement of the casing, the releasable connection being usually spring-pressed, a coiled spring f, being mounted in a recess g, of an upper extension a^x, of the standard a, located above 80 the pivot of the casing, said spring having engagement with a head h, also in said recess, to press said head outwardly so that a wrench seat i, thereof, shall be engaged with the polygonal end j, of the record 85 spindle, the stem k, of said head, being turned usually by the crank handle c, as stated, the outer end of said stem, to which the crank handle is made fast, having a head m, in line with the stem, for use when the 90 stem and the head thereof are to be pulled endwise to release the connection between the same and the record spindle, the casing being then turned upon its pivot and compressing the spring f, said spring expanding 95 and causing automatic engagement of the stem with the next succeeding record spindle, to check the rotary movement of the casing with a platform plate uppermost and to hold the casing stationary. Each 100 platform plate 2 is usually slidably engaged with transverse rods 21, said rods and the record and supply spindles being carried by a stationary side 22 of the casing, the other side 23 of the casing being removable.

105 It is further desirable that the casing be capable of being turned down upon one side, from engagement with one of the standards

a, a' , of the base, in order that the removable side of the casing may be detached and the interior of the casing exposed for convenient insertion and removal of the paper rolls, manipulation of the paper, etc., this being accomplished by providing one standard a , of the casing, with a lower hinge n , the pivot of the casing engaging the opposite standard a' , of the base, being removable from its seat within which it is secured, usually by means of a padlock o , carried by the side a' , and having its pivoted hasp engaging over the pivot, so that when the padlock is unlocked and the hasp turned back, the casing may be turned down to rest upon the opposite side a , a cushion p , being usually employed upon this side and having contact with the support or counter. In this position of the casing the platform plates may be slid in and out upon their guide rods, and the record and supply spindles may be removed and reinserted.

In order that the uppermost face of the casing, which is shown in Fig. 1, as horizontal, shall be capable of assuming and being held in an inclined position, the upper extension a^x , of the standard a , is made separate therefrom, and has a clamp connection q , with the pivot shaft b' , so that when the clamp is released, the extension may be swung around slightly and the clamp tightened to secure the extension in position as adjusted, with the clutch member or head h , in position to engage the uppermost record spindle when the uppermost face of the casing is inclined.

A stationary hand rest r , is usually provided at the front of the casing, and is common to each face of the casing as the faces come uppermost, said rest being carried by the extension a^x , of the standard a , of the case, the extension being usually branched to provide a forward extending arm a^y , thereof, carrying the hand rest.

The hand rest is preferably foldable, being pivoted upon a rod s , so that when the hand rest is slid endwise upon said rod a stud t , of the arm a^y , is released from its seat u , in the end flange of the hand rest, which then may be turned pivotally upon said rod, a spring t' , upon the rod, acting to engage the stud with its seat when the hand rest is returned to normal position.

What I claim is:

1. In an autographic register, a stationary support, a hollow casing pivotally mounted upon said support and having a plurality of faces each of which is provided with a platform plate, a paper supply spindle and a record spindle for each of said faces and an operating device mounted upon said support and common to and having a movable clutch member for releasable driving connection successively with each of the record spindles.

2. In an autographic register, a stationary support, a casing pivotally mounted upon said support and having a plurality of faces each of which is provided with a platform plate, a paper supply spindle and a record spindle for each face of the casing and an operating crank mounted upon said support and common to and having a spring-pressed clutch head for releasable driving connection successively with each of the record spindles, said operating device and clutch head when in driving connection with the spindle acting to hold the casing stationary with a platform plate uppermost.

3. In an autographic register, a stationary support, a hollow casing pivotally mounted upon said support, and having a plurality of faces each of which is provided with a platform plate, a paper supply spindle and a record spindle for each face of the casing, and an operating device mounted upon said support and common to and having a movable clutch member for releasable driving connection successively with each of the record spindles, said support having a hinged standard and a stationary standard and said casing having releasable pivotal engagement with said stationary standard, whereby the casing may be turned down upon one side thereof, the opposite side of the casing being removable.

4. In an autographic register, a stationary support, a casing pivotally mounted in standards of said support and having a plurality of faces each of which is provided with a platform plate, a paper supply spindle and a record spindle for each face of the casing, one of said standards having an upper extension above the casing pivot, and an operating device mounted upon said upper extension and common to and having a movable clutch member for releasable driving connection successively with each of the record spindles.

5. In an autographic register, a stationary support having standards, a casing pivotally mounted in said standards and having a plurality of faces each of which is provided with a platform plate, a paper supply spindle and a record spindle for each face of the casing, one of said standards having an upper extension located above the casing pivot, and an operating device mounted upon said upper extension and common to and having a movable clutch member for releasable driving connection successively with all of the record spindles, said upper extension being pivoted to and having a releasable clamp connection with the standard whereby it may be pivotally adjusted, with the said operating device.

6. In an autographic register, a stationary support having standards, a casing pivotally mounted in said standards and having a plu-

rality of faces each of which is provided with a platform plate, a paper supply spindle and a record spindle for each face of the casing, one of said standards having an upper pivotally adjustable extension located above the casing pivot, and an operating device mounted upon said upper extension, pivotally adjustable therewith, and common to and having a movable clutch member for

releasable driving connection successively 10 with each of the record spindles.

In testimony whereof I affix my signature, in presence of two witnesses.

ULYSSES GRANT CAVE.
